Primary Examiner — Garth Rademaker*Assistant Examiner* — Melanie Pellegrini(74) Attorney, Agent, or Firm — Weiss & Moy, P.C.; Veronica-Adele R. Cao(57) CLAIM

The ornamental design for a locket with flower screen, as shown and described.

DESCRIPTION

FIG. 1 is a perspective view of a locket with flower screen showing my new design wherein the broken lines showing a chain illustrate environment and form no part of the claimed design;

FIG. 2 is a left side view thereof;

FIG. 3 is a right side view thereof;

FIG. 4 is a top view thereof;

FIG. 5 is a bottom view thereof;

FIG. 6 is a front view thereof; and,

FIG. 7 is a rear view thereof.
